Primary Examiner — S. Bryan Reinholdt, Jr.*Assistant Examiner* — Ieisha N Price(57) **CLAIM**

The ornamental design for a fastener, as shown and described.

DESCRIPTION

FIG. 1 is a perspective view of a fastener showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view of FIG. 1.

The broken lines in the drawings and the unshaded areas adjacent to them illustrate portions of the fastener that form no part of the claimed design. The dot-dot-dash broken lines define the bounds of the claim that form no part thereof.
